H. M. CHUBBUCK

COMBINATION COMB AND BRUSH

Filed June 4, 1923

Inventor

Herbert M. Chubbuck.

St. Louis.

Attorney

UNITED STATES PATENT OFFICE.

HERBERT M. CHUBBUCK, OF DULUTH, MINNESOTA.

COMBINATION COMB AND BRUSH.

Application filed June 4, 1923. Serial No. 643,284.

To all whom it may concern:

Be it known that I, HERBERT M. CHUBBUCK, a citizen of the United States, residing at Duluth, in the county of St. Louis and

5 State of Minnesota, have invented certain new and useful Improvements in a Combination Comb and Brush, of which the following is a specification, reference being had therein to the accompanying drawing.

10 This invention relates to a combination comb and brush and has special reference to a novel form of construction of same, the principal object being that of simplicity, while another object is to provide means 15 whereby the comb is entirely surrounded by the bristles of the brush so that the extreme end of the brush may be used without engagement by the comb.

Other objects and advantages of the invention will appear in the further description thereof.

Referring to the accompanying drawing forming part of this application and in which like reference characters indicate like 25 parts:

Figure 1 represents a side elevation of the combination comb and brush;

Figure 2 is a face elevation of the combination part of the brush;

30 Figure 3 is a plan view of the body portion with the back removed, and

Figure 4 is a section on the line 4—4, Figure 1.

The body portion of the brush is illustrated at 1 and the handle, which is an integral part thereof, at 2. The body portion has formed therein the longitudinally disposed slot or opening 3 which extends entirely through said portion, the terminations 35 of said slot being such as to snugly receive the back of the comb 4. The back of the body portion is stepped in respect to the handle extension and a back or cover 5 is provided for same to form a closure there-

40 for. This cover may be fastened in place by means of screws, brads, or glue, as desired, and, by having this cover removable it

is evident that the slot 3 may be formed slightly wider adjacent the back than at the face, so as to insure tight fitting of the comb 50 when placed therein.

Upon either side and about the ends of the slot 3 and upon the face of the body portion is formed a similar slot 6 for the reception of the bristles forming the brush portion of the 55 instrument. This slot however does not pass entirely through the body portion of the comb but is only a recess or channel into which the bristles 7 of the brush are fitted or set, and fixed either by glue, rubber or the 60 like. The particularly novel feature of this instrument is that the bristles of the brush extend wholly about the ends of the comb and are spaced slightly therefrom, so that when the instrument is being used in the 65 brushing of one's mustache or eye brows the same may be readily accomplished by using the forward end of the brush only, when the teeth of the comb would not contact the person of the user. 70

Having thus described my invention, what I claim and desire to secure by Letters Patent, is:

A combined comb and brush comprising a single piece handle and body portion, the latter having a central through slot extending longitudinally thereof for the reception of the comb, and the entire back of the body portion being stepped, a cover for said stepped portion of the body forming a continuation of the handle, and a second slot extending wholly about the first mentioned slot but not entirely through the back, and a row of brush bristles fixed within said surrounding slot and spaced from the comb, substantially as and for the purpose described. 75 80 85

In testimony whereof I hereunto affix my signature in the presence of two witnesses.

HERBERT M. CHUBBUCK.
